UNITED STATES PATENT OFFICE

EDWIN A. EKDAHL, OF BOSTON, MASSACHUSETTS, ASSIGNOR TO AMOS BIRD COMPANY,
OF BOSTON, MASSACHUSETTS, A CORPORATION OF CONNECTICUT

COVER FOR CANS AND THE LIKE

Application filed July 2, 1926. Serial No. 120,028.

This invention has relation to covers for cans, receptacles, or the like, made of metal, and more particularly cans such as are employed as containers for handling and shipping frozen eggs.

A wooden cover is usually employed for closing such cans, the interior surfaces of which are lined with sheet metal. The practice has been to fix the lining by nailing it to the sides of the cover, and to fasten the cover to the can by nailing strips of flexible metal at regular intervals to the marginal portion of the cover, and then to tuck or engage the free end portion of the strip in between a downwardly turned bead and the upper edge portion of the can. Such practice is disadvantageous, from the fact that the strips are nailed to the cover, as, in handling and transportation, the nails are liable to work loose and allow the cover to become loose or unfastened, and from the fact that individual fastening elements are used for retaining the lining in place on the cover.

In accordance with the present invention, therefore, the strips or elements which are utilized for inter-engagement with the can are formed integral with the lining of the cover, so that the nailing operation is dispensed with and a more permanent securing of the cover to the can is afforded and the lining is retained in place on the cover without the need of individual fastening elements, by spinning it over onto the top face of the cover.

On the accompanying drawings, Figure 1 is a section through a side of a can, showing the bead at the rim thereof.

Figure 2 represents a plan view of a cover embodying the present invention, fastened to the can.

Figure 3 illustrates a section on the line 3-3 of Figure 2.

Figure 4 is an enlarged plan view of a portion of the cover, showing a cover fastening element.

Figures 5 and 6, respectively, show detailed sections on the lines 5-5 and 6-6 of Figure 4.

Referring to the drawings, 1 as a whole indicates a can made of metal, such as tin, in

connection with which the cover of the present invention is used. In actual practice, the cans may, for example, be about 12 inches in height and about 10 inches in diameter, or of any other commercial size. The construction of the can, however, forms no part of the present invention, except insofar as it is in combination with the cover.

At the upper edge of the can, the metal is bent downwardly and thence upwardly in the form of a bead 2, of double thickness, which abuts against the rim. The bead constitutes the element of the can for inter-engagement with the fastening elements of the cover. Any other suitable bead construction may be used, if desired.

The cover 3, as shown, is made of wood, and is of the proper size to fit within the can opening. The cover is interiorly lined with sheet metal, which overlies its interior surface and side and is secured to the cover by a flange 4 which is spun over onto the top or exterior surface thereof, and is thus retained in place thereon without the need of nails or other individual fastening elements. The flange 4 is formed so as to project exteriorly from the marginal portion of the cover over the upper edge 7 of the can, and thus also serve as a rim for maintaining the cover on the can.

In accordance with the present invention, moreover, fastening elements 5 are formed integral with the lining of the cover, preferably at regularly spaced intervals, as at each quadrant at the margin thereof. Each fastening element is in the form of a strip, the free end of which is folded back on itself to form an engaging element 6 of double thickness, thereby strengthening the element and giving an edge 6^a, against which a suitable tool may be caused to act.

The cover is secured to the can by tucking the element 6 in between the bead 2 and the seam of the can, as shown in Figure 5, thereby prying the seam away from the upper edge portion of the can at the desired intervals, and effecting inter-engagement of can and cover.

By the practice of the present invention, the use of individual fastening elements is en-

tirely done away with, both in securing the lining to the cover and in fastening the cover to the can, producing thereby a more economical and effective package.

5 Having thus described an embodiment of this invention, it should be obvious that it is susceptible of various changes and modifications without departing from its spirit or scope as defined by the appended claims.

10 I claim:

1. The combination with a can, of a wooden cover for closing said can having a metal lining covering the interior surface thereof and secured thereto by a flanged marginal portion of said lining spun over the exterior surface thereof and projecting exteriorly from the marginal portion of the cover and resting on the upper edge of said can.

15 2. The combination with a can having an exterior bead at the upper edge portion thereof, of a wooden cover for closing said can, having a metal lining covering the interior surface thereof and a series of spaced fastening elements integral with said lining and inter-engaging with the bead of said can.

20 3. The combination with a can having an exterior bead at the upper edge portion thereof, of a wooden cover for closing said can having a metal lining covering the interior surface thereof and secured thereto by a flanged marginal portion of said lining spun over the exterior surface thereof, and a series of spaced marginal fastening strips integral with said lining and inter-engaging with the

35 bead of said can.

40 4. The combination with a can having an exterior bead of double thickness at the upper edge portion thereof, of a wooden cover for closing said can having a metal lining covering the interior surface thereof and secured thereto by a flanged marginal portion of said lining spun over the exterior surface thereof, and a series of fastening strips spaced about the margin of said cover and integral 45 with said lining inter-engaging with the bead of said can, the inter-engaging portion of said strip being of double thickness and presenting an edge against which a tool may be brought.

50 In testimony whereof I have affixed my signature.

EDWIN A. EKDAHL.
